(57) CLAIM

I claim the ornamental design for a cup holder liner, as shown and described.

DESCRIPTION

FIG. 1 is a top, right, rear perspective view showing my new design for a cup holder liner.

FIG. 2 is a right-side view thereof.

FIG. 3 is a left-side view thereof.

FIG. 4 is a top view thereof.

FIG. 5 is a bottom view thereof.

FIG. 6 is a front view thereof.

FIG. 7 is a rear view thereof; and,

FIG. 8 is a top view thereof, shown with unclaimed surrounding structure.

The long dash-dash broken lines depict a boundary line around FIG. 8 and form no part of the claimed design. The short dash-dash broken lines illustrate environmental structure which forms no part of the claimed design.
